DESIGN FOR A SHOESHINE BOX

Joseph T. Pearson, Jr., Huntingdon Valley, Pa.

Application December 8, 1945, Serial No. 124,511

Term of patent 7 years

(Cl. D58—12)

To all whom it may concern:

Be it known that I, Joseph T. Pearson, Jr., a citizen of the United States, residing at Huntingdon Valley, in the county of Montgomery and State of Pennsylvania, have invented a new, original, and ornamental Design for a Shoeshine Box, of which the following is a specification, reference being had to the accompanying drawing, forming a part thereof.

box showing my new design. The side and end not shown are plain.

The dominant or essential features of the design reside in the portions shown in full lines.

I claim:

The ornamental design for a shoeshine box, substantially as shown and described.
